UNITED STATES PATENT OFFICE.

LOUIS P. VALIQUET, OF NEW YORK, N. Y.

DESIGN FOR A HORN-SUPPORTING ARM FOR TALKING-MACHINES.

SPECIFICATION forming part of Design No. 35,873, dated April 15, 1902.

Application filed March 19, 1902. Serial No. 99,029. Term of patent 7 years.

To all whom it may concern:

Be it known that I, LOUIS P. VALIQUET, a citizen of the United States of America, and a resident of the borough of the Bronx, city, county, and State of New York, have invented a certain new and original Design for a Horn-Supporting Arm for Talking-Machines, of which the following is a specification.

Figure 1 is a side view or elevation of the horn-supporting bracket. Fig. 2 is a plan view thereof.

As shown in the drawings, the leading or material features of my design are the transverse double boss A, located about midway of the length of the arm or bracket X, the supporting-rod B, depending therefrom, the downwardly-extending lug C, near the inner end of the bracket, and supporting-web D therefor, outlined and ornamented by the

scrollwork E. The outer half of the bracket is also provided with the supporting-web F on its under side, ornamented with the scroll-work G and the ornamented end piece H. The upper surface of the bracket is provided with the circular openings I, J, and K. (Shown in Fig. 2.)

Having therefore described my invention, what I claim as new, and desire to protect by Letters Patent, is—

The design for a horn-supporting arm for talking-machines, as herein shown and described.

Signed at New York city, New York, this 17th day of March, 1902.

LOUIS P. VALIQUET.
